Inventor:

UNITED STATES PATENT OFFICE.

STEPHEN E. CIBULAS, OF BRIDGEPORT, CONNECTICUT.

SKYLIGHT CONSTRUCTION.

Application filed October 3, 1925. Serial No. 60,239.

This invention relates to glass holding and supporting devices for building structures, and particularly, although not exclusively, for skylights and the like, and has for an object to form an extremely simple glass supporting and clamping structure which may be made of relatively heavy sheet metal so as to make it rigid and lengthen the life of the structure, and which will also be so constructed and arranged that there is no danger of breaking the glass, either in installing or because of expansion and contraction after installation, and further to provide a structure which may be easily assembled.

With the foregoing and other objects in view, I have devised the construction illustrated in the accompanying drawing forming a part of this specification, similar reference characters being employed throughout the various figures to indicate corresponding elements. In this drawing,

Fig. 1 is a transverse section through a skylight involving my improved construction.

Fig. 2 is a transverse section substantially on line 2--2 of Fig. 1, and

Fig. 3 is a perspective view with portions broken away to more clearly show the construction.

The numeral 10 indicates a curb of any suitable construction that is used for surrounding the opening in the roof, and the top and outer surface thereof is covered with the flashing 11. Mounted on the upper edge of this curb is a base member 12 also of sheet metal with a downwardly and outwardly curved portion on the outer side of the curb to form a gutter 13. The outer wall extends upwardly above the top of the curb as shown at 14 and is then bent outwardly and downwardly as shown at 15 to form a seat for the lower edge of the glass 16. The base member drops somewhat below the surface of the glass to form a drip gutter 17 and is then extended upwardly to form a stop wall 18 for the edge of the glass. The gutters 13 and 17 are provided with suitable openings 19 and 20 respectively for exit of moisture.

The side edges of the glass are supported by a supporting bar 21. This bar is made of relatively heavy sheet metal bent to substantially the shape shown, that is, at substantially its mid width it is bent upon itself to form an upright inverted U-shaped body

portion 22 and the side walls are then bent outwardly and upwardly on the opposite sides of this body portion to provide gutters 23 and seats 24 for the glass 16, that is, the glass rests on the free edges of these side portions of the bar as indicated in Figs. 2 and 3. Extending longitudinally at the under side of this bar is a second sheet metal member 25 which has its opposite side edges bent upwardly on opposite sides of the supporting bar as shown at 26 to form sweat gutters beneath the glass. These members extend from the curb 10 to the ridge member 27 and rest at their opposite ends on these members and by which they are supported. The ridge member is bent to substantially the shape shown in Figs. 1 and 3, and may or may not be supported on a ridge beam 28, depending on the size of the structure. A ridge plate 29 rests on the top of this beam and the lower flanges 30 of the ridge member rest on this plate. It will be noted that the ridge member 27 is of relatively heavy sheet metal bent so that the top walls 31 thereof are inclined to substantially the pitch of the glass and then the side walls 32 extend downwardly at right angles to these walls to the flanges 30 which are also substantially of the same pitch as the glass. Thus the upper end of the supporting bar 21 and the gutter member 25 rest on top of the flange 30 with their ends butting against the side wall 32. The height of these members from the top of the seats 24 to the bottom of the gutter member 25 is practically equal to the height of the side walls 32 and also the distance of the seat 15 above the top of the base member on the curb, so that when the glass is placed in position it is supported on all four sides, on the top side on the top wall 31 of the ridge member, on the opposite upright sides or ends on the seats 24 of the supporting bar and at its lower edge on the seat 15 of the base member. There are, therefore, no bending strains on the glass as it is rigidly supported on all four sides.

The glass is held in position by a cap 33 or clamping bar. This cap or clamping bar is also made of relatively heavy sheet metal and is of substantially inverted V-shape so as to straddle the supporting bar 21 and rest at its opposite edges on the tops of the glass above the seats 24, and it cooperates therewith to clamp the glass against these seats. The cap or bar is held in position by

means of bolts 34 passing through the gutter member 25, up through the body portion of the supporting bar and the ridge of the cap. A nut 35 is threaded on this bolt 5 against the top of the body 22 of the supporting bar and clamps the gutter member 25 to the lower side of this bar. A washer 36 is placed on the bolt above the cap with a spring 37 above this washer and held 10 in position by a nut 38. It will be seen that this spring securely clamps the cap or clamping bar 33 against the top of the glass to secure the glass in position. It will also be seen that this spring will allow the cap 15 to yield under expansion or contraction so that there will be no danger of breaking the glass. This also allows the use of a relatively heavy metal for the supporting bar and the cap because it is not necessary that they 20 should yield to allow for this expansion and contraction, and thus the supporting structure may be made heavier and more rigid giving it greater strength and also longer life. It will be noted that the head of the 25 bolt 34 is seated in the bottom of an inverted cup 39 in the gutter member 25. Thus the opening for the bolt is raised above the bottom of the gutter so that moisture cannot leak through this opening. The outer 30 lower end of the cap 33 is closed as shown at 40, to give a finish and prevent entrance of moisture.

The upper edges of the glass are enclosed and also clamped in position by a ridge cap 35 41. This is of sheet metal bent to substantially the form shown and has openings 42 in its side walls to receive the upper end of the cap 33. The upper bolt 43 is similar to the bolts 34 but it also passes through the 40 ridge plate 29, the flanges 30 of the ridge member, the gutter member 25, the top of the body portion of the supporting bar 21 and the ridge cap 41 so as to secure all of these members together. It is not, however, 45 necessary that it should pass through the cap 33 so that the upper end of this cap merely abuts against the side of the bolt, as shown in Fig. 1. This bolt is provided with a spring 37 the same as the other bolts.

50 It will be apparent from the foregoing description that the construction is extremely simple and rigid as it may be made of relatively heavy sheet metal which is bent to form giving a maximum of strength. As the 55 glass is supported on all four sides and is clamped by means mounted to yield under expansion and contraction there is no danger of the glass being broken by strains due to this expansion and contraction. The glass 60 at its upper edge and upright ends is also so mounted that it may move in its supports as it expands and contracts. In installing the glass no putty or other packing is necessary as any moisture which passes under the edges 65 of the cap or clamping bar 33 is carried out

by the gutters 28, and moisture from sweating on the under side of the glass will be carried down into the gutters 25 by which it will be carried to the outer side of the curb and discharged through the openings in 70 the bottom of the gutter 13.

Having thus set forth the nature of my invention, what I claim is:

1. A glass holding structure comprising a sheet metal supporting bar bent upon itself 75 to form an inverted U-shaped body portion and walls extending upwardly from the lower edges of the sides thereof and spaced from said body portion on opposite sides thereof to form gutters to carry moisture 80 and terminating in free edges forming seats for the glass, a longitudinally extending member mounted below said bar having upwardly extending outer edges on opposite sides of said bar spaced from the glass 85 to form a sweat gutter beneath the glass, a cap resting on the top of the glass on opposite sides of said bar, and bolts for clamping the cap to the glass.

2. In a glass holding structure, a supporting bar of sheet metal bent upon itself at substantially its mid width to form an inverted U-shaped longitudinally extending rib, the sides thereof extending laterally away from each other at the lower edges of the rib and the free edges then extending upwardly to form seats for the glass and drain gutters for moisture, a sheet metal member mounted at the under side of said bar and having upwardly extending edges 100 on the opposite sides thereof spaced from the glass to form sweat gutters beneath the glass, an inverted substantially V-shaped cap forming a clamping bar extending longitudinally of the supporting bar above the 105 same and arranged with its free edges co-operating with the seats to secure the panes of glass therebetween, and bolts passing through the sweat gutter, the supporting bar and the cap to clamp them together. 110

3. In a glass holding structure, a supporting bar of sheet metal bent upon itself at substantially its mid width to form an inverted U-shaped longitudinally extending rib, the sides thereof being bent laterally 115 away from each other at the lower edge of the rib and the free edges then extending upwardly to form seats for the glass and drain gutters for moisture, a sheet metal member mounted at the under side of said 120 bar and having upwardly extending edges on the opposite sides thereof spaced from the glass to form sweat gutters beneath the glass, an inverted substantially V-shaped cap forming a clamping bar extending longitudinally of the supporting bar above the 125 same and arranged with its free edges co-operating with the seats to secure the panes of glass therebetween, bolts passing through the sweat gutter, the supporting bar and the 130

cap, a nut on said bolt above the cap, and a spring on the bolt between the nut and the cap.

4. In a glass holding structure, a supporting bar of sheet metal bent upon itself at substantially its mid width to form an inverted U-shaped longitudinally extending rib, the sides thereof being bent laterally away from each other at the lower edge of the rib and the free edges then extending upwardly to form seats for the glass, a sheet metal member mounted at the under side of said bar and having upwardly extending edges at the opposite sides thereof to form sweat gutters beneath the glass, an inverted substantially V-shaped cap forming a clamping bar extending longitudinally of the supporting bar above the same and resting at its free edges on the top of the glass, and bolts passing through the lower member, the supporting bar and the cap to secure them together, the lower member being provided with inverted cupped portions to receive the head of the bolt and to raise the opening for the bolt above the bottom of the gutter.

5. In a skylight construction, a curb, a base member mounted on the top of said curb and extending downwardly and outwardly from the same to form a gutter, said base member then extending above the curb to form an abutment, then outwardly

to form a seat for glass and then upwardly to form an abutment for said glass, a supporting bar for the glass having drain gutters on its opposite sides resting on said base member with its lower end engaging said first abutment, a gutter secured to the lower side of said bar beneath the glass and leading to the first mentioned gutter, a cap extending over the supporting bar and resting on top of the glass, and means for clamping the cap against the glass to secure it in position.

6. In a skylight construction, a curb, a base member mounted on the top of the curb and having a wall extending outwardly and upwardly to form an abutment, then outwardly to form a seat for glass and then upwardly to form an abutment for the lower edge of the glass, a supporting bar seated at its lower end on said base and against the first abutment, said supporting bar having longitudinally extending seats for the glass on the opposite sides thereof, a ridge member having a seat for the upper edge of the glass and a flange to support the upper end of the supporting bar, an inverted V-shaped clamping bar over the supporting bar and resting on the glass, and means for clamping the clamping bar against the glass to hold it in position.

In testimony whereof I affix my signature.
STEPHEN E. CIBULAS.
